(57) **CLAIM**

The ornamental design for a “trailer body”, as shown and described.

DESCRIPTION

FIG. 1 is a perspective view of a trailer body showing my new design;

FIG. 2 is a front elevation view thereof;

FIG. 3 is a rear elevation view thereof;

FIG. 4 is a left side elevation view thereof, the right side elevation view being a mirror image thereof;

FIG. 5 is a top plan view thereof; and,

FIG. 6 is a bottom plan view thereof.

The broken lines showing in the FIGURES are for illustrative purposes only and form no part of the claimed design. My trailer body is characterized by a rounded front, a side-to-side arched top, near-vertical sides, and fenders which flare outward from the front and extend to, and wrap around the rear corners of, the trailer.
